TRACTOR FRAME

Lovell R. Simmons, Willie O. Ray, and Horace H. Ray,
Jackson, Miss., assignors to M-R-S Manufacturing Com-
pany, Flora, Miss., a corporation of Delaware

Filed Feb. 5, 1964, Ser. No. 78,526

Term of patent 14 years

(Cl. D14—3)

Des. 198,841

PAGE 2

FIG. 1 is a front perspective view of a design for a frame for a tractor showing our new design;

FIG. 2 is a right rear perspective view of the tractor frame; and

FIG. 3 is a left rear perspective view of the tractor frame.

We claim:

The ornamental design for a tractor frame, substantially as shown.
